UNITED STATES PATENT OFFICE.

URIAH S. JACKSON, OF OSSYPEE, NEW HAMPSHIRE.

TELEPHONE-SERVICE APPARATUS.

SPECIFICATION forming part of Letters Patent No. 673,796, dated May 7, 1901.

Application filed November 22, 1900, Serial No. 37,390. (No model.)

To all whom it may concern:

Be it known that I, URIAH S. JACKSON, of 5
Ossipee, in the county of Carroll and State of
New Hampshire, have invented a new and
useful Improvement in a Telephone-Service
Apparatus, of which the following, taken in
connection with the accompanying drawings,
is a specification.

My invention relates to that class of tele- 10
phone-service apparatus in which the person
using the apparatus may call up any one on
the system, and in so doing cut out all of the
others, so that there can be no interruption by
a third party; and it consists in an arrange- 15
ment of clockwork and electric devices, which
may be best understood by reference to the
description and drawings.

The object is to furnish an apparatus that
will admit of direct use by any one in the group 20
of users and is simple and comparatively
cheap. This object I attain by use of the
mechanism shown in the accompanying drawings,
in which—

Figure 1 is a front elevation showing the set 25
of instruments used at each station. Fig. 2 is
a side elevation of the same. Fig. 3 is a view
showing in elevation two dials and the dial-
board to which they are connected. This dial-
board has attached to its rear side clock-trains 30
that operate parts connected to said dials.
The cover of the case that contains the dials
is represented as open and is not shown in
full. Fig. 4 shows in elevation the rear side
of the dial-board. Two clock-trains are shown 35
in connection with the electrical mechanism.
The rear part of the box is also shown with
the binding-posts and their connections.
Fig. 5 is a vertical section, enlarged, taken on
line 5 5 of Fig. 1, (parts omitted.) Fig. 6 is 40
a diagrammatical view illustrating the opera-
tion of my apparatus.

The new features of this apparatus are em-
bodied in mechanically-operated clock-trains,
their electrical coöperating devices, and the 45
system of electrical circuits that connect the
said clock-train devices with each other and
with the telephone instruments.

In the drawings, Figs. 1 and 2, I have shown, 50
mounted upon a base A a box B B' B'', which
contains one set of my apparatus, and also
on the same base a telephone instrument T'
R of ordinary construction.

As the pin E' is connected to the receiver 55
R by a cord R', which is made (for a purpose)
so short that the said pin E' cannot remain in
the dial D when the receiver is not in use, it
is obvious that the said receiver R must be
taken from the receiver-holding lever R² be- 60
fore the said pin E' can be inserted in its hole
in the dial, and in thus taking the receiver
R from its lever it is obvious that the said
lever R² would fly up, and thus break the bell-
circuit. To prevent this action of the lever 65
R², I attach to it a hook R³, with which one
finger of the hand that takes the receiver may
engage, and thus hold it and the lever R²
down; but to ring the bell the button R⁴,
Fig. 1, must be pushed in. To do this, I have 70
a bent lever R⁵, with a wire R⁶ suspended
from it. This wire R⁶ has a hook R⁷ near
the hook R³, so that the same finger or another
finger of the same hand that holds the re- 75
ceiver R may be used for drawing down this
hook as well as hook R³—that is, the oper-
ator may with one hand hold the receiver R
and also hold down the lever R² and cause
the button R⁴ to be pushed in, so that he may 80
ring the bell with his other hand.

For convenience in adjusting and repairing 85
my apparatus the box is made of three
parts—namely, a cover B, having circular
openings for showing the dials, a part B',
which serves as a plate to which nearly all of
the actuating parts of the mechanism are at- 90
tached, and part B'', which serves as an outer
casing for protecting the clockworks and their
adjuncts.

In the drawings, D represents a fixed an-
nular dial, having upon it a series of numer- 95
als from "1" to "14" and a zero. These nu-
merals correspond to the number of stations
in the group. A pin-hole is made at each of
the numerals and also at zero. The pin-hole
for the numeral "9" is indicated at E, Figs. 1 100
and 3. The object of these holes is to re-
ceive the stop-pin E', the function of which
will be explained hereinafter.

D' is a rotating disk operated by a clock-
train J, Fig. 4, acting through the arbor D³.
The disk D' has projecting from its under 105
side a series of contact-pins d d, Figs. 3 and
5, (also shown in the diagram, Fig. 6.) Each
of the contact-pins d d serve when in contact
to connect two conductor-plates d³ d², one of

which is indicated by dotted line in Fig. 3 and both in Fig. 5. The contact-plates d^2 d^3 and the pins d d serve to make an electric connection between the operating circuit and the magnets C^{11} C^{11} , Figs. 4 and 5, as will be explained in the operation. The disk D' also has a switch-operating arm D^2 , which acts upon a switch-lever F . This switch-lever F swings upon a pivot F' and gives motion to two switch-bars F^2 and F^3 , which serve to make and break electric connections in the telephone-circuit.

For holding the disk D' in the position, as shown at Fig. 3, in which the arm D^2 is at zero and pressing the switch-lever F (see Fig. 5) over so as to close one set of telephone-lines and open another, I have a notch in the said disk at D^4 , into which a stop-arm K' on the key K enters. To allow the disk to move, the key K is pressed down by the one who desires to use the telephone. Then the disk D' will be rotated by its clock-train and will continue to rotate until the arm D^2 , starting from zero, is checked by the stop-pin E' , which is placed by the operator at the number that designates the number of the station to be called. This motion of the disk D' will cause a number of the pins d d to come successively in contact with the contact-plates d^2 d^3 , and thus cause a series of electrical actions to energize the magnets C^{11} C^{11} , and thus cause the step-by-step hand C' to move around to the number that designates the station to be called. The switch-lever F and the connected switch-bars F^2 F^3 are thrown back into their normal position when released by the passing by of the arm D^2 by the action of a spring F^4 , Fig. 5.

The key K is thrown upward by a spring k , so as to bring the stop-arm K' into its locking position in the notch D^4 of the disk D' and to bring the holding-arm K^2 up through the notch C^4 in the disk C^2 , so that it (the arm K^2) will be above the said disk. By pushing the key down the holding-arm K^2 is carried through the notch C^4 to a position below said disk. When the key K is in its lowest position, the arm K' releases the disk D' , leaving it free to rotate. The arm K^2 does not act as a stop for the disk C^2 ; but the said disk holds the arm K^2 either above or below it, as the case may be—that is, if the key is thrown up to its highest position by the spring k and the disk C^2 , standing at any position in which its notch C^4 does not coincide with the arm K^2 , then the said key cannot be pressed down, and consequently the disk D' cannot be released, and if the key K is in its lowest position then the arm K^2 will rest against the under side of the disk C^2 and will hold the key down until the disk C^2 is made to rotate to its zero position—that is, until the notch C^4 coincides with the arm K^2 . Then the key will be free to rise, (under the pressure of the spring k).

One function of the disk C^2 is to control the movements of the key K —that is, the said

key cannot be moved either up or down unless the notch C^4 of the disk C^2 coincides with the holding-arm K^2 . This notch is so placed that when the index-hand C' stands at "0" it (the notch) coincides with the arm K^2 , and the key is freed from the holding action of the said disk.

The step-by-step dial C is fixed and has upon it numerals from "1" to "14" and a "0." These graduations correspond with those on the annular dial D , already referred to. An index-hand C' traverses the disk C and is made to rotate by the clock-train M , Figs. 4 and 5, acting through the center arbor C^3 . The movement of the hand C' is intermittent or step by step and is regulated by a magnetic escapement device which may be explained as follows: C^{11} C^{11} are electromagnets having an armature C^7 , to which an escapement having pallets C^9 C^{10} is connected by the arm C^8 . The pallets C^9 C^{10} alternately check and release the tooth C^6 on the arbor C^5 . The said arbor is rotated by the clock-train M . The arbor C^3 , that carries the hand C' , also carries a disk C^2 . This disk C^2 has insulated contact-points c c' , which are preferably located immediately under the hand C' , so that their position is always indicated by the hand. The contact-plates for co-operation with the points c c' are four in number, two of which bear constantly upon the upper side of the disk, which, being metallic, forms an electrical connection for the said contact-plates. The other or lower contact-plates t^{34} t^{33} are only operative when the contact-points c c' are in a predetermined position—that is, the position for closing the telephone-circuit of the number called. For convenience the contact-points c c' are placed on the disk C^2 immediately under the index-hand C' for all of the stations; but the contact-plates t^{22} t^{23} and t^{34} t^{35} (see, for example, Fig. 6, station No. 9) are placed in different positions for each station—that is, for station No. 7 the contact-plates are in such a position that the pins will make the contact when the hand points to the number "7," and for station No. 9 the pins will make the contact when the hand points to the number "9," and so on.

The posts L L' L^2 L^3 L^4 , Figs. 3 and 4, are for the outside wires and are electrically connected with the inside wires by the clips l l' l^2 l^3 and n n' n^2 n^3 n^4 when the box is closed.

An ordinary registering device V , Fig. 3, is so placed that at every rotation of the disk D' its arm D^2 will record its rotation, thus automatically registering the number of times that the telephone apparatus has been used.

The disk D' makes a complete rotation for each call—that is, a part rotation is made for the call, and then the rotation is completed by withdrawing the pin E' , so as to allow the disk D' to assume its normal resting position. Hence for each call the arm D^2 on the said disk must come in contact with the lever of the registering device Y .

The operation of my apparatus may be ex-

plained as follows: Referring to Fig. 6, we will assume that station No. 7 wishes to call up No. 9. The user takes down the receiver R, which allows him to insert the attached pin 5 E' in hole No. 9 of the annular dial D, all of the apparatus being in the normal position of rest—that is, the index-hands C' of the disks C² and the arms D² of the disks D' are all at "0." Now by pressing the key K the arm K', 10 Fig. 5, will descend, and thus leave the disk D' free to rotate under the impelling power of the clock-train J. As soon as one of the pins d comes in contact with the contact-plates an electric circuit is formed through 15 all of the magnets C¹¹ C¹¹, thus releasing clock-trains that operate the disks C² and the connected hands C', allowing them to move one division, and as each of the pins d makes a contact with the contact-plates d² d³ a circuit 20 is made and the dials C² and index-hands C' will advance one step or number. This action will go on until the dials and hands have advanced step by step until the arm D² is stopped by the pin E' at hole No. 9—that is, 25 nine pins d have made contacts, and thus have advanced all of the dials C² to the ninth position. In the ninth position, as has already been stated, the contact-points c c' of the dial C² are in electrical contact with the contact-plates t²² t²³ and t³⁴ t³⁵ of station No. 9—that 30 is No. 9 is put into the telephone-circuit and may be called by No. 7. The step-by-step magnetic or operating circuit is as follows: Beginning at one of the pins d d, station No. 35 7, (we will assume that it is the first one to come in contact with the plates d² d³ after disk D' has started to rotate,) the circuit will be wire 1 2 3 4, battery W, wire 5 6 7 8, magnets C¹¹ C¹¹ of station 9, wire 9 10 11 12 13 14, 40 magnets C¹¹ C¹¹ of station 8, wire 15 16 17 18 19 20 21 22, magnets C¹¹ C¹¹ of station 7, wire 23 24 25, plate d⁵ to pin started from. Having caused the dial of station to assume the position desired—that is, in such a position as 45 to bring the contact-points c c' into electric connection with the plates t²² t²³ and t³⁴ t³⁵—that is, to close the telephone-circuit—the said circuit will be as follows: starting from button t, telephone of station No. 7, thence by 50 wire t² t³ t⁴ t⁵, switch-bar F², wire t⁶ t⁷ t⁸, post t⁹, button t¹⁰, wire t¹¹ t¹², plate t¹³, disk C², plate t¹⁴, wire t¹⁵, switch-bar F³, (of station 8,) wire t¹⁶, post t¹⁷, wire t¹⁸, post t¹⁹, wire t²⁰, switch-button of station 9, wire t²¹ t²¹, contact-plate 55 t²², contact-point c in disk C², contact-plate t²³, wire t²⁴ t²⁵ t²⁶ t²⁷ t²⁸ to telephone of station 9, (the one called,) thence back by post t²⁹, wire t³⁰ t³¹ t³² t³³, plate t³⁴, point C' of disk C², plate 60 t³⁵, wire t³⁶ t³⁷ to switch-button, thence by wire t³⁸ t³⁹ t⁴⁰, (wire 11,) wire t⁴¹ t⁴² t⁴³, post t⁴⁴, wire t⁴⁵, switch-button and switch-bar F², wire t⁴⁶ t⁴⁷ t⁴⁸ t⁴⁹, post t⁵⁰, telephone-button t⁵¹ of telephone started from. As soon as the call has been made and the answer received the pin E' 65 is removed from the hole No. 9 and the clock-

work causes the disk D' to continue its rotation, so that the arm D² will be carried around until it comes in contact with and operates the switch-lever F, thus restoring the entire apparatus to its normal resting position. 70

I claim—

1. In a telephone-service apparatus, a telephone-receiver, a bent lever adapted to operate the "push-button" of the telephone, and said push-button; hooks hanging from said bent lever and from the receiver-lever, said hooks being adapted to be operated by the hand that takes the receiver from its lever; and a stop-pin attached to said receiver by a cord adapted to allow said stop-pin to engage 80 with the contact-pin dial, only when the receiver is taken off from its lever, and said contact-pin dial and lever, substantially as and for the purpose set forth.

2. In a telephone-service apparatus, a rotatable disk, a clock-train adapted to operate said disk; contact-pins in said disk adapted to open and close an electric circuit, said electric circuit, adapted to operate mechanism by which an electric circuit is established 90 between the calling-station and the called station; and said circuit between the calling and the called station, substantially as and for the purpose set forth.

3. In a telephone-service apparatus, a rotatable disk; a clock-train, operating said disk; contact-pins in said disk, adapted to open and close electric circuits as described; said electric circuits; a switch; an arm attached to said disk and adapted to hold said switch 100 closed to one line of circuit-wires and open to another; and a spring adapted to reverse said switch when not held by said arm, substantially as and for the purpose set forth.

4. In a telephone-service apparatus, a fixed 105 annular dial having numbered pin-holes, a stop-pin adapted to fit said pin-holes; a rotatable disk concentric with said fixed dial, and having an arm adapted to engage with said pin and hold the said disk in place, until the 110 said pin is removed, by the operator, and contact-pins upon said disk adapted to open and close electric circuits, and said electric circuits, substantially as and for the purpose set forth.

5. In a telephone-service apparatus, a rotatable disk having contact-pins, electric circuits adapted to be opened and closed by said contact-pins and means for operating said disk; a key adapted to automatically spring 120 into place, and hold said disk at its normal position, when not forced down by the user, said key having a holding-arm adapted to engage with a notched rotating disk and be held down or up by said disk except when said disk is in 125 its normal resting position, its notch being then in a position to allow the said arm to pass through, as described; insulated contact-points on said notched disk adapted to engage with contact-plates and close an electric 130

circuit between the calling-station and the called station, substantially as and for the purpose set forth.

6. In a telephone-service apparatus, a step-by-step rotating disk having insulated points adapted to close an electric telephone-circuit connecting the calling-station with the called station; said electric telephone-circuit; mechanism for operating said rotating disk; an escapement device operated by magnets which are adapted to be energized by electric circuits, closed and opened by contact-pins on a

rotating disk, and said disk and mechanism for operating the same, substantially as and for the purpose set forth.

In testimony whereof I have signed my name to this specification, in the presence of two subscribing witnesses, on this 17th day of November, A. D. 1900.

URIAH S. JACKSON.
